UNITED STATES PATENT OFFICE.

HENRY E. ALSTERLUND, OF ROSLINDALE, MASSACHUSETTS.

DESIGN FOR A BADGE, EMBLEM, OR SIMILAR ARTICLE OF MANUFACTURE.

52,518.

Specification for Design.

Patented Oct. 8, 1918.

Application filed June 25, 1917. Serial No. 176,875. Term of patent 14 years.

To all whom it may concern:

Be it known that I, HENRY E. ALSTERLUND, a citizen of the United States, residing at Roslindale, in the county of Suffolk and State of Massachusetts, have invented a new, original, and ornamental Design for a Badge, Emblem, or Similar Article of Manufacture, such as scarf-pins, brooches, emblems, watch-charms, watch-fobs, rings, cuff-links, and other such ornamental articles of jewelry or souvenirs, of which the following is a specification, reference being had to the accompanying drawing, forming part thereof.

The figure represents my new design, shaped in outline to represent an elk's tooth which serves as a background or panel for the other features of the design shown thereon.

I claim:

The ornamental design for a badge, emblem, or similar article of manufacture, as shown.

HENRY E. ALSTERLUND.
